UNITED STATES PATENT OFFICE.

MAURICE D. LARKIN, OF DAYTON, OHIO.

RELIEF-VALVE.

SPECIFICATION forming part of Letters Patent No. 678,405, dated July 16, 1901.

Application filed November 17, 1900. Serial No. 36,899. (No model.)

To all whom it may concern:

Be it known that I, MAURICE D. LARKIN, a citizen of the United States, residing at Dayton, in the county of Montgomery, State of Ohio, have invented certain new and useful Improvements in Relief-Valves, of which the following is a specification, reference being had therein to the accompanying drawings.

This invention relates to relief-valves for use in connection with liquid-conducting lines wherein the liquid is transmitted under pressure, particularly fire-extinguishing apparatus.

The invention has for one object to improve the structure disclosed in Patent No. 606,053, granted June 21, 1898, to L. O. Dehnel, so as to insure the quick and positive operation of the relief-valve when the pressure in the line is increased by closing the escape-outlet and also to permit a free discharge of the liquid under pressure through the valve.

A further object of the invention is to provide a structure of flap-valve which when not in use will leave the passage through the casing free from obstruction and when raised will have sufficient throw to effect the relief operation.

A further object is to provide a construction of piston and cylinder which will when in one position effect a full and free discharge of the liquid under pressure and in the opposite position effectually prevent such escape when the outlet from the line is opened.

Other objects and advantages of the invention will hereinafter appear in the following description, and the novel features thereof will be particularly pointed out in the appended claims.

Referring to the drawings, Figure 1 is a vertical section through the valve; Fig. 2, an end elevation of the same with the relief conducting-pipe removed. Fig. 3 is a perspective of the flap-valve, and Fig. 4 is a similar view of the piston-casting.

Like letters of reference indicate like parts in the several figures of the drawings.

The letter A indicates the valve-casing, which is provided at opposite ends with suitable screw-threads for attachment to hose, pipes, or other liquid-conducting lines. It will be understood that this valve is ordina-

rily applied between the engine, hydrant, or other source of pressure and the conducting hose or line, so as to prevent the bursting of the latter when the outlet therefrom is closed and the pressure therein consequently greatly increased. This casing is provided with a relief-port A' and valve seat or pocket A², adapted to receive and contain a flap-valve B. The relief-port is formed with a cylinder C, having at its outer open end a series of guide-fingers C', spaced from each other to permit the free discharge of water between the same. Suitably connected to the relief A' is a relief conducting-pipe A³, which receives the discharge from the cylinder C. Within the cylinder a piston D is located and provided with a stem D', having upon one side a series of rack-teeth D² and upon the opposite face a guide-rib D³, by which means a straight and accurate movement of the piston is insured within the cylinder. This structure also insures the easy movement of the piston and obviates the necessity of using any adjusting devices therefor. The flap-valve B is pivoted within the casing by means of a pin or bolt B', and upon its hub is formed a series of rack-teeth B², adapted to mesh with those upon the valve-stem D'. The flap-valve is suitably curved in cross-section and at its free end B⁴ to conform to the curvature of the casing and the seat A² therein. In order to effect a free and easy movement of the flap-valve, an enlarged path or way A⁴ is provided in the casing to the extent of the travel of the flap-valve. The curved sides B³ of this valve serve to distribute the pressure thereon and direct the liquid therefrom, so as to permit a movement of the valve through a body of liquid under pressure without difficulty.

In the operation of the invention when the flap-valve B is lying in the position shown by dotted lines in Fig. 1 the water or liquid has a free passage through the casing, as the valve is located within the seat A² and offers no obstruction thereto. At this time the piston is disposed within the cylinder, so as to close the outlet-ports between the guides C'. Now if the outlet from the hose or pipe be closed and the pressure upon the liquid continues the increase within the pipe or hose is very rapid and tends to burst the same.

Under these conditions this pressure is transmitted to the piston D and the same forced outward from the cylinder, thus permitting the water under pressure to be discharged 5 between the guides and around the piston. These guides extend to the full limit of movement of the piston, and thereby prevent the packing - ring thereof from expanding and catching on the edge of the cylinder, while 10 the rib upon the piston-stem forms a true and continuous guide for its movement and maintains the rack-teeth in proper alignment with the teeth upon the flap-valve. As soon as the outlet from the hose is opened the 15 pressure of the water acts upon the surface of the flap-valve and by reason of its area forces it to its seat, thus returning the piston to the cylinder and closing the relief-port. The present structure of valve permits a 20 greater travel than heretofore, and therefore causes a quicker action of the parts and a full closing of the relief. Under previous constructions of relief-valves when the outlet was closed the pressure within the hose increased from twenty to forty pounds, while 25 with the present construction of flap-valve and relief-port the maximum increase does not exceed five pounds.

It will be obvious that changes may be 30 made in the details of construction and configuration of the several parts without departing from the spirit of the invention as defined by the appended claims.

The use of the curved valve and case presents an important improvement in this art, 35 as it prevents the escape of water around the edges of the flap-valve. The curved end B⁴ of the flap-valve corresponds to the shape of the case, thus effecting a close fit between the 40 valve and case to prevent the passage of water around the valve. The curved body of the flap-valve adapts the same to rest in the recess of the case without offering any obstruction to the passage of water. The curved 45 form also permits a much longer travel than heretofore, thus increasing the movement of the relief-piston, and facilitates the escape of a larger amount of water through the port. The close fit of the valve causes the same to 50 quickly operate under all conditions.

While this invention has been described in its relations to prevent the bursting of hose, still it may be applied to prevent damage to machinery, engines, hydrants, pumps, and 55 any class of devices wherein a moving body of liquid or vapor is used under pressure.

Having described my invention and set forth its merits, what I claim, and desire to secure by Letters Patent, is—

60 1. A relief-valve comprising a casing, a relief-port therein, a piston in said port, a stem from said piston having at opposite points rack-teeth and a longitudinally-extending guide-rib engaging the casing, and a flap-

valve pivoted in the casing and provided with 65 teeth to engage those upon said stem, substantially as specified.

2. A relief-valve comprising a casing, a cylindrical relief-port having an open end, a piston adapted to travel within and beyond 70 the end of said port, a stem from said piston provided with a guide-rib and rack-teeth thereon, and a flap-valve pivoted within the casing and provided with means to engage the teeth upon said stem, substantially as 75 specified.

3. A relief-valve comprising a casing, a cylindrical relief-port having an open end and guide-fingers extended beyond the body portion thereof, a piston in said port adapted to 80 travel over said fingers, a stem from said piston provided with rack-teeth, and a flap-valve pivoted within the casing and provided with means to engage said teeth, substantially as 85 specified.

4. A relief-valve comprising a casing provided with a seat in its wall, a relief-port for said casing, a piston in said port, a flap-valve curved to fit said seat, and means for connecting said valve and piston, substantially 90 as specified.

5. A relief-valve comprising a casing, a relief-port therein, a piston in said port, a stem from said piston having upon one face a longitudinal guide-rib and upon the opposite 95 face a series of rack-teeth, and a valve within the casing adapted to mesh with said teeth and operate said stem, substantially as specified.

6. A relief-valve comprising a casing, a cylindrical relief-port having spaced guide-fingers extended beyond its open end, a piston in said port adapted to traverse said fingers, a valve within said casing, and means connecting said valve and piston for simultaneous movement, substantially as specified. 100

7. A relief-valve comprising a casing having a valve seat or pocket and an enlarged path or way therein, a flap-valve curved in cross-section and pivoted within the casing 110 to travel in said path and to lie within said seat, a relief-port from the casing, and means controlled by said valve for opening and closing said port, substantially as specified.

8. A relief-valve comprising a casing provided with a curved seat in its wall and a curved path, a flap-valve pivoted in said casing and having a curved body to conform to said seat and a curved end to conform to said path, and means for operating said valve; 120 substantially as specified. 115

In testimony whereof I affix my signature in presence of two witnesses.

MAURICE D. LARKIN.
